US0D1053350S

(12) **United States Design Patent** (10) **Patent No.:** **US D1,053,350 S**
(45) **Date of Patent:** **** Dec. 3, 2024**

(54) **HANDHELD DEVICE**

(71) Applicant: **CANARY MEDICAL SWITZERLAND AG**, Baar (CH)

(72) Inventors: **Jeffrey M. Gross**, Carlsbad, CA (US);
Peter J. Schiller, San Marcos, CA (US); **Kevin Gemmell**, San Diego, CA (US); **Luis Dogue**, San Marcos, CA (US)

(73) Assignee: **Canary Medical Switzerland AG**, Baar (CH)

(**) Term: **15 Years**

(21) Appl. No.: **29/805,814**

(22) Filed: **Aug. 30, 2021**

(51) LOC (14) Cl. **24-02**

(52) U.S. Cl.

CLAIM

The ornamental design for a handheld device, as shown and described herein.

DESCRIPTION

FIG. 1 is a top perspective view of a handheld device showing our new design;

FIG. 2 is a bottom perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The broken lines shown in the drawings represent portions of the handheld device that form no part of the claimed design.

1 Claim, 7 Drawing Sheets
